UNITED STATES PATENT OFFICE.

LYNN J. HARRINGTON, OF PHILADELPHIA, PENNSYLVANIA, ASSIGNOR TO L. C. SMITH & BROS. TYPEWRITER COMPANY, OF SYRACUSE, NEW YORK, A CORPORATION OF NEW YORK.

PLATEN FOR TYPE-WRITERS.

1,230,295.

Specification of Letters Patent. Patented June 19, 1917.

Application filed October 6, 1910. Serial No. 585,720.

To all whom it may concern:

Be it known that I, LYNN J. HARRINGTON, a citizen of the United States, and resident of Philadelphia, county of Philadelphia, State of Pennsylvania, have invented certain new and useful Improvements in Platens for Type-Writers, of which the following is a specification.

In preparing stencil plates upon the typewriter for addressing machines, and in other similar work, the surface of the typewriter platen becomes indented and worn in the particular place or zone used and when ordinary platens are used for this class of work considerable expense is incurred for platen renewals. This invention relates to a platen, a portion of the surface layer or cover of which is removable and interchangeable with other like portions, a supply of which can be provided at slight cost. The invention further relates to means for sustaining the removable portion in position on the platen, means for sustaining the work in proper relation to the removable portion and means for positioning the platen for writing on the work when so sustained. In addition to preparing stencils, the improved platen is especially adapted for writing on cards, envelops and other small sheets. The invention will be described in connection with the accompanying drawing in which,

Figure 1 is a side elevation of a platen embodying the invention;

Fig. 2 is a section on the line 2—2 of Fig. 1;

Fig. 3 is a view of the right end of the platen;

Fig. 4 illustrates a stencil blank which the platen is adapted to receive.

Referring to the drawing, A indicates a platen which may be of the usual construction except as hereinafter noted. The body of the platen consists of a core 10 of wood or similar material and the covering 11 of hard rubber or like material. The platen is provided with the usual shaft sections 12, knobs or twirlers 13 and feed ratchet 14.

The covering of the platen includes a removable section 11^a which is preferably but slightly larger than the cards or envelops for which the platen is to be used. That is, the removable section of the cover is a segment of a cylinder and usually less in length than the platen. In the instance illus-

trated the platen is adapted for writing stencil addressing cards of the character illustrated in Fig. 4. These cards comprise thin panels 15 upon which addresses are written or perforated and frames or sustaining borders 16.

The removable surface section of the platen 11^a is retained in position, as illustrated, by metal clips 17, 18, which hold it firmly on the core 10 but permit it to be withdrawn endwise. Below the lower clip 17 is a holding strip 19, the lower edge of which is secured to the platen while the upper edge extends outward, forming a pocket to receive and hold the lower edge of the card or other article to be written upon. In Fig. 2 a card 20 is shown in dotted lines in position for printing. As shown in Fig. 1 a shoulder or projection 21 on the platen adjacent to the edge of the holding strip 19 is in position to engage the left end of the card and position it upon the platen.

It is desirable to limit the revolution of a platen, when printing cards, to enable the operator to set it rapidly for the first line on each card and to prevent it from being turned backward more than is necessary to bring all parts of the card to the printing point. As shown in the drawing, a gage piece 22 is adjustably connected to the platen at its right end by means of screws 23 passing through slots 24. The part 22 has downwardly turned gaging projections 25, 26, which coöperate respectively with fixed stops 27, 28, to limit the rotary movement of the platen, the stops being suitably connected to the carriage.

In the practical use of the invention the same platen can be used indefinitely, the sections 11^a being removed and replaced as often as may be necessary. A great saving in expense of writing on small cards or sheets is thus effected. This is particularly notable in preparing stencils for addressing machines as the paper on which the addresses are cut is very thin and is operated upon by the bare type, no ribbon being necessary. In such work the platen is very rapidly worn and indented so as to unfit it for use and by simply replacing the worn section according to this invention the work may be carried on continuously at slight expense.

It will be understood that my invention is

applicable to platens of the various typewriters now on the market regardless of their size or length. Of course a platen provided with a removable section and suitable gages, as above described is not adapted for general use in typewriting but machines as usually constructed permit of the removal and replacement of the platen without difficulty and it is understood that platens made according to my invention are to be interchangeable with the ordinary platens of various typewriters.

Having described my invention what I claim and desire to secure by Letters Patent is,

15. 1. A cylindrical typewriter platen having clips for holding a removable segmental cylindrical surface section thereon, and means for positioning a card or stencil over said removable section.
20. 2. A typewriter platen having a segmental section of its cylindrical covering material removable, clips connected with the platen and overlapping said removable section for securing the same in operative position, and means for positioning a card over

said removable section both laterally and longitudinally.

3. A rotatable typewriter platen provided with a removable segmental cylindrical cover section and with stops for limiting the rotary movement of the platen to prevent the removable section from being turned away from the printing point.

4. A typewriter platen provided with a removable segmental cylindrical cover section and a card holding device adjacent thereto for sustaining the card over the removable section.

5. A rotatable typewriter platen having a removable segmental cylindrical cover section, a card holding device for holding a card over said removable cover section, and stops for preventing the card from being turned away from the printing point.

In testimony whereof I affix my signature in presence of two witnesses.

LYNN J. HARRINGTON.
